(57) **CLAIM**

We claim the ornamental design for a cup with handle, as shown and described.

DESCRIPTION

FIG. 1 depicts a front side of the cup with handle, in isometric view. The dashed line areas comprise no part of the claimed design, and indicate the environment for a container lid that might be used with the cup of the claimed design.

FIG. 2 depicts a front view of the cup with handle. The dashed line areas comprise no part of the claimed design, and indicate the environment around the cup.

FIG. 3 depicts a back view of the cup with handle. The dashed line areas comprise no part of the claimed design, and indicate the environment around the cup.

FIG. 4 depicts a right side view of the cup with handle. The dashed line areas comprise no part of the claimed design, and indicate the environment around the cup.

FIG. 5 depicts a left side view of the cup with handle. The dashed line areas comprise no part of the claimed design, and indicate the environment around the cup.

FIG. 6 depicts a top view of the cup with handle. The dashed line areas comprise no part of the claimed design, and indicate the environment around the cup; and,

FIG. 7 depicts a bottom view of the cup with handle. The dashed line areas comprise no part of the claimed design, and indicate the environment around the cup.

1 Claim, 7 Drawing Sheets
